PACKAGED SET OF GAME PIECES

Guglielmo Frascolla, New York, N. Y.

Application October 5, 1956, Serial No. 43,241

Term of patent 14 years

(Cl. D34—5)

FIG. I.

FIG.3.

FIG.2.

FIG.4.

Fig. 1 is a top plan view of a packaged set of game pieces showing my new design;

Fig. 2 is a bottom plan view of same; and

Figs. 3 and 4 are edge views of the package shown in Fig. 1, the edges not shown being substantially identical thereto.

I claim:

The ornamental design for a packaged set of game pieces, substantially as shown and described.
